FRIEDRICH BERGIUS, OF HANOVER, GERMANY, ASSIGNOR, BY MESNE ASSIGNMENTS,
TO THE CHEMICAL FOUNDATION, INC., A CORPORATION OF DELAWARE.

PROCESS FOR OBTAINING LIGHT HYDROCARBONS FROM HEAVY HYDROCARBONS.

1,344,671.

Specification of Letters Patent. Patented June 29, 1920.

Application filed February 12, 1914. Serial No. 818,224.

To all whom it may concern:

Be it known that I, Dr. FRIEDRICH BERGIUS, chemist, a citizen of the German Empire, residing at Hanover, Germany, have 5 invented certain new and useful Improvements in or Relating to Processes for Obtaining Light Hydrocarbons from Heavy Hydrocarbons, of which the following is a specification.

- 10 Processes already exist by which light hydrocarbons such as benzin, gasoline and the like are produced or split off from heavy hydrocarbons, such as petroleum and the like, by heating. The yield of the lighter 15 hydrocarbons, produced by these simple heating processes, is, however, comparatively small because of the large production of less readily condensed gases on the one hand and of carbonaceous residues on the other hand.
- 20 Furthermore, because of the production of these less readily condensed gases, the lighter hydrocarbons obtained by these processes, generally known as cracking processes, are of inferior quality and have 25 an objectionable smell, containing large amounts of unsaturated hydrocarbons; they are colored and deposit carbon when burned.
- The object of the present invention is to avoid the disadvantages just mentioned by 30 converting all unsaturated compounds produced into saturated compounds. This can be accomplished by adding hydrogen to the said unsaturated compounds. While such "hydrogenation" has been attempted heretofore, it has not been altogether satisfactory and it is the purpose of the present invention to provide an improved method of hydrogenation which shall be free from disadvantages hitherto existent.
- 40 According to my invention, about to be described, I cause hydrogen to react with unsaturated hydrocarbons by bringing them together at a very high pressure and high temperature. Instead of pure hydrogen, 45 mixtures of hydrogen with other gases, especially mixtures of hydrogen with neutral gases which do not react with the unsaturated hydrocarbons such as nitrogen, methane and carbon monoxid, could be used. In the case of mixed gases, however,
- it must be remembered that the pressure of such mixed gases must be suitably higher in order that the partial pressure due to the hydrogen *per se* may have the desired value of at least 20 atmospheres. Motor spirits 55 obtained in this manner differ from the usual products of cracking processes by being colorless, having very little smell, and burning at high efficiency without any substantial formation of soot. Chemical examination of the products shows that but a small percentage of unsaturated compounds is included in the same.
- In carrying out my improved process, I heat heavy hydrocarbons as, for example, 60 petroleum, its distillation products and residues, or heavy hydrocarbons obtained from bitumen and the like, in a rupture proof vessel in the presence of free or dissolved hydrogen and at a pressure for the hydrogen of at least 20 atmospheres; preferably I employ temperatures in excess of 250° C. for several hours. The product is then transferred to a distilling apparatus in which the light hydrocarbons which have 65 been formed are distilled off and fractionated. The remaining heavy residue can either be further treated in a second similar operation, or used without further change as 70 fuel oil.
- Aside from the superior quality of the lighter hydrocarbons obtained by my process just described, I also obtain a very large yield of said lighter hydrocarbons, the losses 75 caused by the formation of carbonaceous residues and of gaseous products of combustion amounting only to a few per cent. Such comparatively large yields can only be obtained when petroleum is heated under 80 high pressure as above set forth.
- It has been found that a very large percentage yield of light hydrocarbons can be obtained from the decomposition of heavy hydrocarbons if, during the process of decomposition, the production of gaseous 85 products is held back as much as possible by the application of high pressure to said heavy hydrocarbons. The means for producing this pressure may act directly in the vessel containing the heavy hydrocarbons, 90
- 95
- 100

or in a vessel communicating with said first named vessel. The means may be mechanical, such as, for example, a piston placed under pressure; or it may be gaseous.

5 To effectually hold back the gaseous products and prevent their escape from the heavy hydrocarbons requires a pressure of at least 20 atmospheres and a pressure of 30 atmospheres is preferable. If a gas is used as the 10 pressure medium and forced into the reaction chamber in a cold state, the pressure with which it is so forced in should be in excess of 15 atmospheres.

It has been found that the process just 15 described makes it possible to simultaneously remove sulfur from the materials treated and to effect this removal in a quantitative manner by using metals, metal oxids or hydroxids as the desulfurizing means. In effecting 20 the desulfurizing, it is generally sufficient to have a temperature of 300° C. at a pressure of about 50 atmospheres, the heating varying from one half hour to two hours. The use of the mentioned desulfurizing 25 means facilitates the reaction for converting heavy hydrocarbons into light hydrocarbons and shortens the time required for such reaction.

My improved process may be carried out 30 with various types of apparatus. The accompanying drawings show, in a somewhat diagrammatic fashion, types of apparatus which I have found satisfactory. In these drawings, Figure 1 shows a construction of 35 apparatus in which the pressure medium is applied in the reaction vessel itself; and Fig. 2 shows a construction in which the pressure medium is applied in a vessel which communicates with the reaction vessel.

40 In the drawing, 1 is the rupture proof reaction vessel into which the heavy hydrocarbons to be treated are introduced through a pipe 2 having a high pressure valve 3. A pipe 4 leads to a tank 5 which contains hydrogen or a mixture of hydrogen and other gases as previously set forth under pressure which is used as a pressure medium; this pipe is provided with a high pressure valve 6 and a pressure gage 7. Pipe 2 projects 45 but a short distance into the reaction vessel 1 and the pipe 4 preferably projects well below the surface of said hydrocarbons as indicated at 8; in this way, the hydrogen or hydrogen and other gas mixed which is 50 admitted into the reaction vessel simultaneously stirs the heavy hydrocarbons and at the same time mixes with them. If the stirring of the hydrocarbons, produced by the gas, is not sufficient for thorough mixing, 55 a stirring device (not shown) may also be employed. The temperature of the hydrocarbons is determined by a thermometer (not shown) inserted in the thermometer pipe 9. A pipe 10 with valve 11 is arranged at

the bottom of the reaction vessel 1 for discharging the products resulting from the reaction, which products are carried away for further treatment by distillation.

Referring to Fig. 2, the reaction vessel is designated by the numeral 12 and the liquid hydrocarbons are supplied to it through a pipe 13 having a valve 14. In use, the reaction vessel is fairly completely filled with the liquid hydrocarbons, the remaining space being filled with hydrogen or with mixed 75 gas containing hydrogen. Tank 12 is connected by pipe 15 to a vessel 16 partly filled with heavy hydrocarbons. Pressure in the direction of arrow 17 is exerted on the surface of the liquid in tank 16 by means of a 80 suitable piston P or by means of liquid hydrocarbons which are pumped into tank 16 at suitable pressure; or the surface of the liquid in tank 16 may be acted upon by a suitable gas pressure. Pipe 18 serves to introduce the heavy hydrocarbons into tank 16.

In the constructions, both of Fig. 1 and Fig. 2, tanks 1 and 12 are respectively heated in any preferred manner as, for example, by furnace gases which may be caused to pass 90 through the pipes F.

The following example is typical of the operation of my improved process.

Example: 10 kg. of Galician gas oil with boiling point between 270° C. and 360° C. 95 were placed in a rupture proof vessel. Hydrogen at a pressure of 100 atmospheres was then pumped into the reaction vessel and the vessel tightly closed and heated to about 400° C. After 12 hours heating, the contents 100 of the vessel, weighing 9.7 kg., were removed and fractionally distilled.

The quantities and weights of distillate were obtained as follows:—

Up to 60° C.	1.2 kg.	105
Between 60° C. and 120° C.	1.5 kg.	
Between 120° C. and 150° C.	0.9 kg.	
Between 150° C. and 180° C.	0.9 kg.	
Between 180° C. and 250° C.	1.9 kg.	
Between 250° C. and 300° C.	1.2 kg.	110
Between 300° C. and 360° C.	1.8 kg.	
Over 360° C.	0.3 kg.	

The several distillates had very little odor, were colorless and remained so even when 115 stored for a long time.

Claims:

1. The process of obtaining light hydrocarbons from heavy hydrocarbons which comprises heating the heavy hydrocarbons 120 in contact with and under a pressure of hydrogen exceeding 20 atmospheres.

2. The process of obtaining light hydrocarbons from heavy hydrocarbons which comprises heating the heavy hydrocarbons 125 in contact with and under a pressure of hydrogen of about 100 atmospheres.

3. The process of obtaining light hydro-

carbons from heavy hydrocarbons which comprises heating the heavy hydrocarbons in contact with and under a pressure of hydrogen exceeding 20 atmospheres, and maintaining the working temperature during the operation at about 400° C. and at not less than 250° C.

4. The process of obtaining light hydrocarbons from heavy hydrocarbons which comprises heating the heavy hydrocarbons

in contact with and under a pressure of hydrogen of about 100 atmospheres and maintaining the working temperature at about 400° C. and not less than 250° C.

In testimony whereof I affix my signature 15 in presence of two witnesses.

DR. FRIEDRICH BERGIUS.
